UNITED STATES PATENT OFFICE.

HERBERT S. MORLEY, OF NEWTON CENTER, MASSACHUSETTS.

PROPELLER.

1,072,249.

Specification of Letters Patent.

Patented Sept. 2, 1913.

Application filed November 11, 1912. Serial No. 730,612.

To all whom it may concern:

Be it known that I, HERBERT S. MORLEY, a citizen of the United States, and a resident of Newton Center, in the county of Middlesex and State of Massachusetts, have invented a new and useful Improvement in Propellers, of which the following is a full, clear, and exact description.

This invention relates generally to reversible propellers, and the improved construction is characterized by auxiliary blades for preventing racing of the engine when the propelling blades are being reversed.

The particular embodiment of the invention comprises a hub carrying propelling blades and retarding blades, the said blades being articulated so that when the propelling blades are reversed the retarding blades, which are normally inoperative, come into operative position, so that the tendency of the engine to race is prevented.

Reference is to be had to the accompanying drawings forming a part of this specification, in which like characters of reference 25 indicate corresponding parts in all the views, and in which—

Figure 1 is a side view of the improved structure, showing the retarding blades in inoperative position; Fig. 2 is a side view, 30 partly sectional, showing the retarding blades in operative position; Fig. 3 is a plan view showing the retarding blades in inoperative position; Fig. 4 is a sectional view on the line 4—4 of Fig. 1; while Fig. 5 is 35 a perspective view setting forth the block carrying the propeller blades.

The propeller as an entirety is made up of a hub 1 having a sleeve 2 extending therefrom, the propelling blades 3 extending laterally from the hub and the retarding blades 4 lying alongside the hub and being movably supported in position. The particular construction of the hub 1 contemplates the said sleeve 2 and a longitudinally 40 extending opening 5, within which a block 6 is slidably mounted, being fixed to the end of a rod 7 extending through the interior of the said sleeve 2, the said rod being movable in order to bring about reversal of the propeller blades. Extending transversely of 45 the block 6, and through an opening 8 therein, are the stub shafts 9, carried by the said propeller blades 3: as previously mentioned, the retarding blades 4 extend normally 50 alongside of or longitudinally with the hub 1, as shown particularly in Fig. 1, these re-

tarding blades being provided with suitable openings adjacent their ends through which the said stub shafts 9 at the ends of the propelling blades pass. The ends of the retarding blades 4 adjacent the said openings are provided with gear teeth 10 engaging with the racks 11 carried on opposite sides of the said hub 1. Extending transversely of the propelling blades 3, and adjacent their inner 55 ends, are the arms 12 having slots 13 adjacent their outer ends into which the pins 14, extending laterally from the said hub 1, enter.

Referring particularly to Figs. 1 and 3, 70 the propelling blades 3 are shown in operative position, that is, extending at a suitable angle with respect to the said hub, so that when the hub is turned the said blades will be turned therewith and will serve the 75 usual functions of a propeller. In these same figures the retarding blades 4 are in inoperative position, that is, extending longitudinally of the said hub and closely adjacent the sides thereof, in order that as little 80 friction as possible may result, the edge portions 15 of these blades, and the adjacent end portions 16 of the hub, being suitably beveled or chamfered in order to promote such result. If now the rod 7 is moved toward the left of Fig. 1, or into the position 85 shown in Fig. 2, the engagement of the said arms 12 at the ends of the propelling blades with the pins 14 will turn these blades through a certain angle into the position 90 shown in Fig. 2, so that if the engine is running when such change is made the resistance which such blades offer to the water is materially reduced, the result being a tendency of the engine to race; however, in such 95 position (that is, as shown in Fig. 2) the retarding blades 4 have been brought away from the end portion of the hub 1 and now extend laterally therefrom, with the sides of the said retarding blades engaging the water, 100 the effect of such a position of the retarding blades being to prevent such described racing of the engine. This position of these retarding blades is brought about by reason of the engagement of the 105 gear teeth 10 at the ends thereof with the said racks 11 on the hub 1. If, now, the rod 7 is moved farther to the left, the travel of the block 6 within the said opening 5 in the hub 1 will turn the propelling blades into 110 positions substantially at right angles to the position shown in Fig. 1, so that with the

engine turning in the same direction, the direction of travel of the boat is reversed; with such position of the propeller blades the retarding blades have come closely adjacent the said hub 1 and extend in a direction opposite to the direction of extension shown in Fig. 1; that is, the propelling blades have been reversed and the retarding blades have had their positions changed through 180°, the middle position of such 10 retarding blades being broadside to the water so that they exert a damping effect on the engine. At intermediate positions of the propelling blades the retarding blades also occupy intermediate positions, the combined action of the blades being such that the speed of the engine is maintained substantially uniform.

A consideration of the drawings and descriptive matter will make clear the fact that the retarding blades place no added load on the engine in any position; when in operative position, that is, when the propelling blades are inoperative, the said blades serve to prevent racing, and when these retarding blades are in the position shown in Fig. 1, they lie closely adjacent the hub, and the frictional resistance of the water on such blades does not affect the efficiency of 30 the construction since there is no component of any force due to the presence of such blades to be overcome by the engine when working.

While the drawings set forth the preferred construction and relation of parts to bring about the function contemplated, it is, of course, clear that different elements may be availed of in order to impart the relative movement to the retarding blades and the 40 propelling blades, and it is therefore clear that the spirit of the invention could be described by an equivalent arrangement of such blades effecting the result disclosed.

Having thus described my invention, what 45 I claim as new and desire to secure by Letters Patent is:—

1. A reversible propeller comprising propelling blades and retarding blades, means for reversing the propelling blades, the retarding blades normally extending in the direction of travel of the boat and presenting their broadsides to the water when the propelling blades are at right angles to the direction of movement of the boat.

55 2. A reversible propeller comprising a hub, a block movable longitudinally of the hub, propelling blades movably carried by the block, means between the hub and the propelling blades whereby when the block is moved the blades will be reversed, and retarding blades adapted to be moved when the block is moved, the retarding blades being thereby brought from inoperative to operative position.

65 3. A reversible propeller comprising a

hub, a block movable longitudinally thereof, propelling blades movably carried by the block, means whereby movement of the block reverses the said blades, and retarding blades moving with the said block and having a common center of motion with the said propelling blades.

4. A reversible propeller comprising a hub having an opening therein, the hub being provided with a sleeve whereby a 75 turning movement may be imparted thereto, a block within the opening, a rod extending from the block whereby it may be moved, propelling blades movably carried by the block and extending laterally from the hub, 80 arms carried by the said blades, pins carried by the hub engaging the arms, whereby when the block is moved the blades will be reversed, retarding blades moving with the said block, racks carried by the hub, and 85 gears carried by the said retarding blades whereby they are moved simultaneously from an inoperative position through an operative position as the said propelling blades are reversed.

90 5. A reversible propeller comprising a hub, a member movably carried thereby, propelling blades carried by the member, retarding blades also carried by the member, and means whereby, when the said member 95 is moved longitudinally of the hub, the retarding blades will be brought from a position on one side of the propelling blades to another position on the other side of the propelling blades, the said second position 100 being diametrically opposite the first one.

6. A reversible propeller comprising a hub, a member movable longitudinal thereof, propelling blades movably mounted on the member, means co-operatively associated with the hub and the propelling blades, whereby movement of the said member will turn the said blades through substantially 90°, retarding blades movably mounted on the said member, and means co-operatively 110 associated with the hub and the blades, whereby the retarding blades will be moved through substantially 180° when the said propelling blades are moved.

7. A reversible propeller comprising a 115 hub, an element movable longitudinally thereof, propelling blades movably carried by the said element, means co-operatively associated with the hub and the said blades, whereby they will be reversed when the element is moved, and retarding blades adapted to be moved from inoperative to operative position through movement of the propelling blades, the center of movement 120 of the blades traveling longitudinally of the hub.

8. A reversible propeller comprising a hub, an element movable longitudinally thereof, propelling blades movably mounted on the element, retarding blades movably 130

mounted on the element, the said blades having a common center of movement, and means associated with the hub and the blades, whereby the retarding blades move through substantially 180° while the propelling blades move through substantially 90° .

9. A reversible propeller comprising a hub, an element movably mounted thereon, 10 propelling blades movably carried by the element, retarding blades movably carried by the element, the blades having a common center of movement, movement of the said element moving the center of movement of 15 the said blades with respect to the hub.

10. A reversible propeller comprising a hub having an opening therein, the hub being provided with a sleeve whereby a turning movement may be imparted thereto, a 20 block contained within the opening, means extending from the block and through the

said sleeve, whereby the block may be moved independently of the hub, propelling blades movably mounted on the block and extending laterally from the hub, arms carried by the said blades, pins carried by the hub and engaging the arms, retarding blades movably mounted on the said block, racks carried by the hub, and gears carried by the said retarding blades, movement of the block 30 longitudinally of the hub reversing the propelling blades and bringing the retarding blades from an inoperative position through an operative position and into a final inoperative position.

In testimony whereof I have signed my name to this specification in the presence of two subscribing witnesses.
